SASH HANGER

Arthur C. Soule, San Francisco, Calif.

Application November 7, 1928, Serial No. 317,754
Renewed August 7, 1931

10 Claims. (Cl. 16—179)

This invention relates particularly to a mounting for supporting and controlling the opening and closing movements of an individual sash or a plurality of sashes or other analogous 5 inclosures.

An object of the invention is to provide a mounting for sashes that will be superior in point of simplicity, inexpensiveness of construction, positiveness of operation and facility and 10 convenience in use and general efficiency.

A further object of the invention is to provide a mounting or mountings for supporting a sash or a plurality of sashes, or other analogous inclosures, within an enclosing frame; for controlling 15 and regulating the opening and closing movements of the sash or sashes and having means thereon to regulate the friction of the moving parts of the sash mountings.

A still further object of the invention is to 20 provide in combination with a window frame and plurality of sashes, of means interposed between the sashes and frame to maintain the sashes in any desired opened or closed position against wind pressure and the like.

Other objects and advantages will appear as 25 this description progresses.

In this specification and the annexed drawing, the invention is illustrated in the form considered to be the best, but it is to be understood 30 that the invention is not limited to such form, because it may be embodied in other forms, and it is also to be understood that in and by the claims following the description, it is desired to 35 cover the invention in whatsoever form it may be embodied.

In the accompanying one sheet of drawings:

Fig. 1 represents a plan section through the window frame having a sash mounted therein on a sash hanger constructed in accordance 40 with my invention.

Fig. 2 is an enlarged vertical section in condensed form, taken through Fig. 1 on the line 2—2 showing the sash hanger interposed between the top and bottom edges of the window 45 sash and supporting frame.

Fig. 3 is an enlarged plan view of one of the sash hangers.

Fig. 4 is an enlarged side elevation of the hanger shown in Fig. 3, in the closed position.

Fig. 5 is a cross section taken through Fig. 4 on the line 5—5.

Fig. 6 is a cross section taken through Fig. 4 on the line 6—6.

Fig. 7 is a cross section taken through Fig. 4 on the line 7—7.

This invention relates particularly to a sash hanger or other equivalent sash operating structure, that is adapted to be positioned at corresponding points on either the opposite sides or ends of a sash, for supporting and controlling the movements of the sash in all open, closed and reversed positions. I have illustrated a vertically positioned sash equipped with my sash hangers and adapted to open on a vertical plane, but it is to be understood that the type of sash hanger shown could be applied equally as well to a sash that is adapted to open on a horizontal plane. Likewise, it is to be clearly understood, as being within the contemplated scope of the invention, that the sash hanger will operate in a practical 60 and efficient manner on all different types of metal windows and transoms, even though the present drawing shows the sash hanger associated with a wooden structure.

In detail, the construction illustrated in the drawing includes a window frame composed of a sill 1, stool 2, and side jambs 3, connected across the top by a lintel 4, together with the usual stops 5, and the other weather proof finish, mounted on the interior and exterior of the 65 jambs, sill and lintel. The window frame, as described, is constructed to receive, in a completely operative manner, the window sash 6. The window sash 6 is supported within the window frame by complementary sash hangers secured, respectively, to the top and bottom ends of the sash, and frame, when the sash is of the "casement type", or the sash hangers are interposed between the opposite sides of the sash and window frame, when the sash is of the 70 "awning type". The sash hangers on which the sash is supported in the window frame, are complementary, and each are secured at corresponding points on opposite sides of the sash, whereby both of the hangers will be operated 75 simultaneously and in unison. The sash hangers on the opposite sides of the sash or on the opposite ends of the sash, are identical in construction and in operation.

For the reason that the sash hangers that support the sash in operative position in the window frame are exact duplicates, a description of the construction of but a single hanger will be made and it is to be understood said description will apply to the other hanger.

Each hanger consists of an elongated metal plate 7, having each of the opposite ends 8 and 9 thereof bent to extend below the under surface of the plate 7. The opposite sides 10 and 11 of the plate are bent downwardly to a point 100

105

110

substantially flush with the bent ends of the plate, whereby all of the bent portions of the plate will engage the surface of the window frame to which the same is to be attached and to position the surface of the plate 7 in spaced relation to the surface of the window frame. The plate is provided with a plurality of holes therethrough to provide means for securing said plate through the agency of screws, nails or the like, to the window frame.

The plate 7 is provided with an elongated slot or guideway 12 therein, said slot having an end thereof adjacent the end 9 of the plate, extended toward one side of the plate. The major length of the slot 12 extends parallel with the opposite longer sides of the plate, except for the one end of the slot which is directed toward one side of the plate for the purpose to be hereinafter described. Adjacent the end 8 of the plate, I have provided a pair of matching slots 13 and 14, each of which are curved on the same radius, and both of said slots extend across the width of the plate 7. An arm or link 15 has one end thereof arranged over the slots 13 and 14 and a pair of screws 16 and 17 on the end of said arm extend through the slots 13 and 14 into threaded engagement with a resilient plate 18 positioned below the said plate, so that by adjusting the screws 16 and 17, it is possible to regulate the frictional resistance of the arm 15 and plate 18 relative to the upper and lower faces of the plate 7. Where it is desired to move the arm 15 freely, the screws 16 and 17 will be loosened to provide a minimum resistance between the arm and plate, and where it would be desired to decrease the ease or freedom with which the arm 15 should move the screws 16 and 17 would be adjusted to increase the frictional resistance of the arm relative to the plate.

The opposite end of the arm 15 is pivoted at 19 to the under side of a plate 20 to be used for operatively supporting a window sash 21 in the opening formed by the window frame. The arm 15 is pivoted to the plate 20 near one end thereof, while the opposite end of said plate is provided with a shouldered pin or pivot 22 thereon that is slidably confined in the slot or guideway 12. The plate 20 is suitably perforated to provide screw holes through which screws can be passed for securing the sash onto the sash plate, and the end of the plate 20 is turned upwardly as at 23 to provide a flanged end through which screws are adapted to be passed into engagement with a side or end rail of the sash. The height of the flange 23 permits the lower edge of the sash to be adjusted relative to the upper surface of the plate 20 in order to locate the sash in a predetermined position 60 in the window frame. Ordinarily the sash is rested on the sash plate and screwed thereto, whereas it is possible to secure the sash in spaced relation to the sash plate by first passing screws through the flange plate 23 to hold the sash 65 away from the surface of the sash plate. When the sash plate 20 and arm 15 are in the closed position shown in Fig. 4, the sash plate 20 lies substantially flush with the end 7 of the guide plate. The clearance space between the under side of the guide plate and the surface of the window frame, is sufficient to allow for the head 70 of the sash plate rivet 22 to slide freely therein. The sash hanger is completely assembled as shown in Figs. 3 and 4 into a four part fixture 75 prior to securing it in operative position in the

window frame. When the hanger is mounted in the window frame, as shown in Figs. 1 and 2, one of the longer sides thereof is fitted snugly against the shoulder X, provided on the outside of the sill, stool, jambs and lintel. The sash plate of the hanger is attached onto the sash before mounting the guide plate of the hanger in position on the window frame.

When the sash 6 is attached on the opposite sash plates of the hangers, mounted on opposite sides of the window frame, the inner face of the rails and stiles of the sash will lie in faced contact with the shoulder X provided on the sill, jambs and lintel of the window frame. When the sash is in the closed position in the window frame, the sliding and pivoted end of the sash will lie snugly in contact with the shouldered side of the window frame. When it is desired to open the sash, the free end thereof is forced outwardly to thereby cause the sliding and pivoted end of the sash to travel lengthwise in the guideway 12, and to swing the supporting arm 15 outwardly against the tension of its adjusting screws. It is normally the practice on sashes of the swinging or sliding type, to round off a corner of the sash next the shoulder X on the window frame to permit the sash to be opened and reversed. My sash hanger is so constructed that it is unnecessary to round off the inside corner of the sash so that it may be opened and reversed in the window frame due to the fact that the guideway for the sliding sash is curved to direct the sash outwardly away from the shoulder X on the window frame, a sufficient distance that the sliding edge of the sash will clear the shoulder on the window frame when it is opened and reversed. The curvature in the guideway at one end thereof, causes the sash to fit snugly and tightly into the window frame when it is closed, whereby wind, rain and the like, are prevented from passing around the outside of the sash, and past the window frame into the area on the inside of said window frame. The curvature on the guideway which regulates and controls the movement of the sash, also maintains the sliding end of the sash in spaced relation to the shouldered portions of the window frame so that at all times the sash is free to be opened, closed, or reversed in the window frame without danger of any part of the sash coming into contact with the window frame during the opening and closing movement thereof. The adjusting screws on the sash plate supporting arm 15, control the entire operation of the hanger, whereby the sash may be placed in any desired position without fear that wind pressure or the like will cause the position of the sash to be changed. The sash supported on my sash hangers does not require any auxiliary or additional mechanism for holding the sash in a closed or open, or partly open, or reversed position. With my sash hanger, the sash may be substantially reversed in the window opening so as to present the outside surface of the sash to the interior of the room to facilitate washing.

Although I have shown and described the plate 7, containing the curved guideway, formed integrally with the plate on which the supporting arm is pivoted, and also slidably and pivotally related to the sash supporting plate, it is to be understood that the guideway supporting arm and sash plate could be made of separate elements, and made to operate in that manner in contradistinction to the unit type of fixture shown and described.

Having thus described this invention, what I claim and desire to secure by Letters Patent is:

1. A sash hanger comprising a guide plate having a guideway therein extended lengthwise of the plate, one end of the guideway being curved inwardly toward the edge of the guide plate, and a pair of curved slots arranged in matching relation across the width of the plate at the end thereof opposite the guideway; a sash plate having an end thereof slidably pivoted in the guideway; and a carrier arm pivoted at one end to the sash plate and slidably pivoted at its other end to the curved slots in the guide plate. 80
2. A sash hanger comprising a guide plate having a guideway therein extended lengthwise of the plate, one end of the guideway being extended inwardly toward the edge of the guide plate, and a pair of curved slots arranged in matching relation across the width of the plate at the end thereof opposite the guideway; a sash plate having an end thereof slidably pivoted in the guideway; a carrier arm pivoted at one end to the sash plate and having the opposite end thereof arranged over the curved slots on the guide plate; and adjusting screws on said end of the carrier arm slidably confined in the curved slots to control the swinging movement of the arm and to adjust the frictional relationship between the arm and guide plate. 85
3. A sash hanger comprising a guide plate having a guideway therein extended lengthwise of the plate, one end of the guideway being extended inwardly toward the edge of the guide plate, and a pair of curved slots arranged in matching relation across the width of the plate at the end thereof opposite the guideway; a sash plate having an end thereof slidably pivoted in the guideway; a carrier arm pivoted at one end to the sash plate and having the opposite end thereof arranged over the curved slots on the guide plate; a friction plate beneath the curved slots in the guide plate; and adjusting screws on the carrier arm slidably confined in the curved slots to control the swinging movement of the arms and engageable with the friction plate to regulate the frictional contact of the carrier arm and friction plate with the opposite sides of the guide plate. 90
4. A sash hanger comprising a guide plate having a guideway therein, said plate having the sides thereof flanged downwardly to position the guideway in spaced relation to the surface on which the hanger is mounted; an arm pivoted at one end to the guide plate; a sash supporting plate pivoted to the free end of the arm and having an end of said sash plate provided with a pin thereon slidably confined in the guideway. 95
5. A sash hanger comprising a guide plate having a guideway therein that lies in parallel alignment with the sash when the sash is in the closed position, said slot having an end thereof extended inwardly, said plate having the sides thereof flanged downwardly to position the guideway in spaced relation to the surface on which the hanger is mounted; an arm pivoted at one end to the guide plate; a sash supporting plate pivoted to the free end of the arm and having an end of said sash plate provided with a pivot thereon slidably confined in the guide- 100
- way, the curved end of the guideway guiding the pivoted end of the sash outwardly to permit the sash to be swung from the closed into the open position, and vice versa, without said sash striking the window structure supporting the hanger. 105
6. A sash hanger comprising a guide plate having a guideway thereon, said plate having the sides thereof flanged downwardly to position the guideway in spaced relation to the surface on which the hanger is mounted; a sash plate having an end thereof slidably pivoted in the guideway; and a carrier arm pivoted at one end to the sash plate and slidably pivoted at its other end to the guide plate. 110
7. A sash hanger comprising a guide plate having a guideway therein extended lengthwise of the plate, one end of the guideway being curved inwardly toward the edge of the guide plate, and a pair of curved slots arranged in matching relation across the width of the plate at the end thereof opposite the guideway, said plate having the sides thereof flanged downwardly to position the guideway in spaced relation to the surface on which the hanger is mounted; a sash plate having an end thereof slidably pivoted in the guideway; a carrier arm pivoted at one end to the sash plate and having the opposite end thereof arranged over the curved slots on the guide plate; and adjusting screws on said end of the carrier arm slidably confined in the curved slots to control the swinging movement of the arm and to adjust the frictional relationship between the arm and guide plate. 115
8. A sash hanger comprising a plate having a guideway therein; an arm pivoted at one end to the guideway; a sash plate pivoted at one end to the free end of the arm and pivoted at its other end to the guideway, said sash plate having the pivoted end thereof flanged upwardly to provide for holding the sash in spaced relation to the upper surface of the sash plate, to permit the sash to be adjusted into a properly fitted position in the window frame on which the hanger is mounted. 120
9. A sash hanger comprising a guide plate having a guideway therein extended lengthwise of the plate, one end of the guideway being curved inwardly toward one edge of the guide plate; a sash plate having an end thereof slidably pivoted in the guideway and the other end free to swing across the edge of the plate opposite to that toward which the curved guideway extends; and a carrier arm pivoted at one end to the sash plate and slidably pivoted at its other end to the guide plate at the end thereof opposite the guideway. 125
10. A sash hanger comprising a guide plate having a guideway thereon, said guide plate being disposed in its entirety above its supporting surface without countersinking into said surface; a sash plate having an end thereof slidably pivoted in the guideway; a carrier arm pivoted at one end to the sash plate and slidably pivoted at its other end to the guide plate; and friction creating means on the hanger to retard free movement thereof. 130
